TONE ARM

Lloyd J. Andres, Chicago, Ill., assignor to Permo,
Incorporated, Chicago, Ill., a corporation

Application February 26, 1952, Serial No. 273,381

1 Claim. (Cl. 274—23)

1

This invention relates in general to phonographs and more particularly to a tone arm for playing disc records. The novel features of the tone arm embrace construction which permits quick detachment of the tone arm from a phonograph with simultaneous disconnect of the transducer conductors. The construction also provides static vertical balance of the arm to permit playing of records that are tilted and inherently providing frictionless non-vibratory vertical pivoting and adjustment means for applying predetermined needle pressure. Provision is also made for a mute switch which is automatic in its operation when the tone arm is raised and lowered for playing.

These and other long sought features and advantages are absent in tone arms previous to this invention.

The principal object of the invention is the provision of a spring mounted balanced tone arm which may be quickly removed and replaced for needle and/or transducer substitution.

Another object of the invention is the provision of adjustment means for varying the vertical force supplied to the needle for playing.

Another object of the invention is the provision of a spring suspension for minimizing the transmission of transient vibration to the tone arm through its support.

A further object of the invention includes switch means for automatically short circuiting the transducer when the arm is moved toward its inoperative rest position.

These and other objects and advantages in one embodiment of the invention are shown and described in the following specification and drawing in which:

Fig. 1 is a side elevation of the arm in playing position with a portion shown in cross section;

Fig. 2 is a side elevation of the tone arm in rest position showing a cross section different than shown in Fig. 1;

Fig. 3 is a cross sectional end view of the arm taken through section line 3—3 Fig. 1;

Fig. 4 is a cross sectional end view of the arm taken through section line 4—4 Fig. 1;

Fig. 5 is an enlarged perspective view showing a fragmentary portion of the tone arm disconnected from its support.

Referring to Fig. 1 the tone arm 1 made from insulating material is supported by vertical spindle 2 which spindle is adapted to be raised, lowered and rotated by means not shown. In the position shown, the needle 3 secured in transducer 4 is in playing contact with record 5. A socket

2

member 6 is adjustably retained on the upper end of spindle 2 by screw 7. A counterweight 8 secured to the rear portion of the tone arm is proportioned to vertically balance the weight of the forward end of the tone arm about axis a—a.

Referring to Fig. 5 the socket member 6 is made from insulating material and contains two conventional tip jacks 9—9 spaced as shown. A pair of springs 10—10 are secured at one end to the tone arm by individual laterally spaced screws 11—11 shown Figs. 1 and 4. A pair of plug tips 12—12 are secured in opposite ends of springs 10—10 and bridged by insulator 13 retained as shown by tips 12. The spacing of tips 12 is identical to the spacing of the jacks 9—9. A shoulder screw 14 shown in Figs. 2 and 4 threaded through the tone arm projects through a hole in insulator 15 which straddles springs 10. Since the springs 10—10 are normally biased upward, it is apparent that the screw 14 may be adjusted to vary the normal tension of both springs 10 to adjust the vertical pressure on needle 3. A stop member 16 secured to the tone arm normally projects through the space between the two springs 10 and under the insulator 13. This stop member prevents the springs from being over-stressed in an upward direction when the tone arm is removed by upward force sufficient to disengage the tips 12 from the jacks 9. A T-shaped mute blade 17 is retained to the tone arm under stop 16 and is positioned in the path of movement of the upper ends of the tips 12—12. Thus, when the mute blade 17 is resting on the tips 12, a short circuit is applied to the transducer which is normally connected by conductors to the lugs 18—18 of the springs 10 respectively. The tip jacks 9—9 are normally connected to individual conductors for transmitting the output of the transducer to an amplifier.

In operation and referring to Fig. 2, the elements of the tone arm are shown in their normal rest position with the needle 3 disengaged from the record 5 and the mute blade 17 resting on the upper ends of tips 12 by virtue of the tilting tension in springs 10. Thus when spindle 2 is in its rest position, the needle is held away from the record and the blade 17 applies a short circuit to the transducer.

When the spindle 2 is lowered to a predetermined position, the needle 3 will engage the record 5 and the tone arm will tilt vertically substantially about axis at right angles to (a) and the blade 17 will move upward away from contact with pins 12 and permit the output of the transducer to be transmitted through the tip jacks 9 to an amplifier not shown, and the

tone arm is free to undulate in a vertical direction with a substantially constant needle pressure, by virtue of the resilience in springs 10-10.

It is to be noted that since the forward end of the tone arm is intended to be balanced by the counterweight 8, there will be no inertia force present tending to dislodge the needle from the record in a lateral direction due to a tilted position of the phonograph. It is also apparent that because of the resilient nature of the springs 10-10 that transient vibration in the spindle 2 will be absorbed through springs 10 and not will be transmitted to the transducer, thus eliminating distortion in the output thereof.

It is also apparent that the tone arm may be quickly removed by lifting the arm in a vertical direction and disengaging tips 12 from the tip jacks 9.

Having described my invention, I claim:

A quick detachable tone arm comprising an arm with a transducer secured in one end for playing phonograph records, said arm statically balanced about a horizontal axis, a vertical shaft adapted for predetermined movements along its axis, a socket support secured to the upper end of said shaft, a pair of electrically independent sockets in said support adapted to be connected to a pair of output conductors, a pair of electrically independent flat springs secured at one end in parallel spaced relation in said arm and positioned substantially parallel thereto, each of said springs having a pin secured in its free

end and positioned normal thereto for holding engagement in each of said sockets respectively, a pair of conductors connecting said springs to said transducer for completing a circuit to said sockets, said springs formed to normally bias the transducer of said arm in a downward direction, a substantially flat mute blade secured in said arm above said springs and positioned to contact and short circuit said springs when said arm is in rest position, whereby the downward movement of said shaft a predetermined distance will engage said transducer with a record and pivot said arm about said horizontal axis against the tension of said springs to release contact of said mute blade against said springs and apply a predetermined pressure of said transducer against said record.
